UNITED STATES PATENT OFFICE.

MAX BRESLAUER, OF CHARLOTTENBURG, GERMANY, ASSIGNOR TO THE FIRM OF W. GRAAFF & COMPAGNIE GES. MIT BESCHR. HAFTUNG, OF BERLIN, GERMANY.

FROST-PROOF FIRE-EXTINGUISHING LIQUID.

No. 914,233.

Specification of Letters Patent.

Patented March 2, 1909.

Application filed November 9, 1906. Serial No. 342,663.

To all whom it may concern:

Be it known that I, MAX BRESLAUER, a chemist and a doctor of philosophy, a subject of the German Emperor, and a resident 5 of 29 Kleiststrasse, in the city of Charlottenburg, near Berlin, Kingdom of Prussia, and German Empire, have invented a certain new and useful Frost-Proof Fire-Extinguishing 10 Liquid, of which the following is a specification.

This invention relates to a fire extinguishing liquid which is distinguished by strongly fire extinguishing properties and which is also proof against freezing at very low temperatures in winter of about 45 to about 15 50 degrees C. below zero. The fire extinguishing liquid, which may be thrown upon the hearth of a fire by any available means, consists of a solution of acetate of alkali, for instance of a solution of acetate of ammonia 20 in water. To this solution an addition of glycerin may be made, which however is not absolutely necessary.

The acetates of alkali possess the very 25 important property of adapting themselves completely to the conditions prevailing in the case of chemical fire extinguishers.

The fire extinguishers of known construction, present the inconvenience of freezing- 30 up at low temperatures, so that they will then be unavailable in case of need. It has not been possible heretofore to remedy this difficulty, inasmuch as the substances to be used in this connection are either apt to form 35 compounds with the chemical solutions contained in the apparatus, which greatly interfere with the operation of the fire extinguishing apparatus even making it inoperative, or the substances in question are inflammable 40 themselves and are apt to produce deleterious results when projected upon timber or houses on fire.

The known chemical fire extinguishers are filled generally with a soda solution, to which 45 an acid, in the majority of cases, muriatic acid is added, when the apparatus is to be used in order to generate carbonic acid, and to produce the pressure upon the fluid for this class of apparatus. Now, chlorid of lime for instance might be considered as a substance adapted to prevent freezing of the

fire extinguishing liquid, yet, this substance is entirely unfit for use in apparatus of the kind described, in view of the fact that carbonate of lime would be precipitated by the 55 addition of chlorid of lime to the soda solution and would choke the apertures of the extinguisher, however, the use of this agent would be out of the question on account of its strongly hygroscopic properties, for when 60 this agent is projected upon burning timbers, jointly with the ordinary fire extinguishing liquid, it would be a cause for the production of dry rot in buildings. The acetates of alkali, the acetate of ammonia for instance, 65 on the other hand are well adapted for use in connection with the soda solution. Without giving rise to precipitates, they render said solution entirely frost proof even at a temperature of about 45 degrees to about 50 70 degrees C. below zero, without any possibility of the apparatus getting clogged up and without depriving the solution of its property of generating carbonic acid by reaction with the muriatic acid. Moreover, the fire extinguishing 75 property of the fire extinguishing liquid of the chemical fire extinguishers is very considerably increased by the addition of the acetates of alkali.

In charging an ordinary chemical fire extinguishing apparatus I use bicarbonate of soda 0.67 kg. acetate of ammonia 3.33 kg. water 10 liters. I can add to this solution 3.33 liters of glycerin but it is not absolutely necessary.

Having thus described my invention what I claim is:

1. Frost-proof fire extinguishing liquid which consists of a solution of acetate of alkali and bicarbonate of alkali in water in 90 the proportions specified.

2. Frost-proof fire extinguishing liquid which consists of a solution of acetate of ammonia and bicarbonate of soda in water in 95 the proportions specified.

In witness whereof I have hereunto signed my name this 25th day of October, 1906, in the presence of two subscribing witnesses.

MAX BRESLAUER.

Witnesses:

HENRY HASPER,
WOLDEMAR HAUPT.
